UNITED STATES PATENT OFFICE

158,707

TELEVISION CABINET

Samuel E. Adler, Chicago, Ill.

Application November 23, 1948, Serial No. 149,787

Term of patent 14 years

(Cl. D56—4)

To all whom it may concern:

Be it known that I, Samuel E. Adler, a citizen of the United States and resident of Chicago, in the county of Cook, State of Illinois, have invented a new, original, and ornamental Design for a Television Cabinet, of which the following is a specification, reference being had to the accompanying drawings, forming a part thereof.

Fig. 1 is a front perspective view of a television cabinet, showing my new design;

Fig. 2 is a sectional view taken on line 2—2 of Fig. 1; and

Fig. 3 is a sectional view taken on line 3—3 of Fig. 2.

I claim:

The ornamental design for a television cabinet, as shown.

SAMUEL E. ADLER.
